UNITED STATES PATENT OFFICE.

PETER POWELL, OF BOSTON, MASSACHUSETTS, ASSIGNOR OF ONE-HALF TO JAMES ROSENFIELD, OF BOSTON, MASSACHUSETTS.

AIR-BAG.

1,329,208.

Specification of Letters Patent. Patented Jan. 27, 1920.

Application filed April 15, 1918. Serial No. 228,541.

To all whom it may concern:

Be it known that I, PETER POWELL, a citizen of the United States of America, and resident of Boston, in the county of Suffolk 5 and State of Massachusetts, have invented new and useful Improvements in Air-Bags, of which the following is a specification.

This invention relates to air-bags adapted to be used in repairing automobile tires and 10 for other purposes and more particularly to a tubular air-bag adapted to fit into a section of an automobile tire casing and to expand the section of the casing while it is being vulcanized or otherwise treated.

15 The principal objects of the present invention are to provide an air-bag the various functions of which are performed by different parts which may be respectively replaced, to provide an air-bag which possesses 20 strength and durability, which has strong ends, which is effective for its intended purpose throughout its entire length, which may be inflated through one end while in a tire casing, and to provide a simple and effective 25 method of producing an air-bag of the character referred to.

Other objects of the invention will be apparent from the following description and accompanying drawings, in which,—

30 Figure 1 is a side elevation of an air-bag embodying the present invention, a portion of the bag being shown in section on line 1—1 of Fig. 2;

Fig. 2 is an elevation of the right-hand 35 end of Fig. 1;

Fig. 3 is a left end elevation of the bag in partially completed form;

Fig. 4 is a transverse section on line 4—4 of Fig. 1;

40 Fig. 5 is a side elevation of the inner tube of the air-bag before one end of the tube has been secured in position, this figure illustrating my improved method of closing the end of the inner tube;

45 Fig. 6 is a side elevation of a portion of the outer casing of the air-bag viewed from the bottom of Fig. 1; and

Fig. 7 is a longitudinal central section of a modified form of outer casing.

50 My improved air-bag comprises essentially an outer casing 1 and an inner tube 2, the inner tube adapted to be inflated and the outer tube adapted to restrain the expansion of the inner tube. The outer tube is prefer- 55 ably expansible only to a slight extent and

may be formed of canvas or other suitable material. The inner tube is air tight and is preferably formed of rubber.

A cardinal feature of the present invention consists in closing the ends of the tubular bag in such manner that the bag is of substantially uniform diameter throughout and does not taper inwardly at its ends. This is preferably accomplished by employing rigid flat end members in the outer 60 casing adapted to prevent the inner tube from bulging out at the ends. The inner tube is also made substantially flat so as to fit against the flat ends of the outer casing.

A preferred method of closing the ends 70 of the outer casing is illustrated in Figs. 1, 2, and 3, where disks 3 and 4 of steel or other material possessing the necessary degree of rigidity are disposed on the inside and outside respectively of the end of the 75 casing. The end of the tubular casing 1 is notched so as to provide a plurality of pointed sectors 5 (Fig. 5) and these sectors are bent inwardly between the inner and outer disks 3 and 4. A series of rivets 6 80 pass through the disks 3 and 4 to clamp the sectors 5 between the disks, and as shown in Fig. 3 I preferably provide a rivet for each sector of the casing. I may also provide disks 7 and 8 of canvas or other suitable material between the sectors 5 and the disks 3 and 4 respectively.

In order to permit the insertion and removal of the inner tube I provide means for opening and closing the outer casing, 90 which is preferably comprised as follows: The outer casing is split on its inner side throughout its entire length as shown at 9 in Fig. 4, and secured on opposite sides of the split 9 are interfitting means for securing together the edges of the casing on opposite sides of the opening 9. These interfitting means preferably comprise two metallic plates 10 and 11 secured along the inner side of the casing 1 adjacent the opening 9 and having interfitting loops 12 and 13 extending alternately into the opening 9 so that the openings in the loops are in alignment. A rod 14 is inserted lengthwise through the openings in the loops 12 and 13, 100 thereby securely holding the casing closed at the opening 9. In order to prevent the inner tube from coming into contact with the metallic plates 10 and 11 I may provide a flap 15 of canvas or other suitable ma- 110

terial between the metallic plates and the inner tube and this flap is preferably secured to the casing at one side of the plates, as for example at 16. A suitable means for securing the plates 10 and 11 to the casing 1 comprises two series of rivets 17 and 18 passing respectively through the plates and through the casing adjacent the opening 9.

As above stated the end of the inner tube is preferably made flat so that the inner tube will conform to the contour of the outer casing, and the present invention comprises an improved method of forming an air tube having flat ends, the preferred

embodiment of this method being substantially as follows: A flat rigid member such as illustrated at 19 in Fig. 5 is inserted in the end of the air tube and the edges 20 of the tube are bent over the flat member 19.

20 A flat end member, such as illustrated at 21 in Fig. 1, may then be vulcanized or otherwise secured to the bent-over edges 20 of the tube. After the end has been secured to the bent over edges the member 19 is removed

25 from the tube. In closing the first end of the tube the member 19 may be removed from the opposite open end of the tube or may be shifted to the opposite end of the tube preparatory to closing the opposite end.

30 However, after both ends have been closed the member 19 may only be removed through an opening in the side of the tube, such an opening being shown at 22 in Fig. 5. After the member 19 has been removed the open-

35 ing 22 is sealed by vulcanizing or other suitable means. The member 19 is preferably of substantially the same peripheral contour as the air tube 2, and when the tube 2 is circular in cross-section, as is 40 usually the case, the member 19 preferably comprises a circular disk. In this connection it will be understood that the word "disk" as herein employed does not necessarily mean a circular disk unless so specified.

45 While the disk 19 employed for closing the ends of the air-tube may be of substantially the diameter of the tube 2, or even of somewhat less diameter, it is preferably made larger in diameter so that the tube 2 is expanded when the disk is inserted thereinto, as shown for example in Fig. 5. In this way the bent-over edges of the tube extend outwardly beyond the periphery of 55 the tube so that the portion of the tube to which the end is to be secured is disposed in a perfectly flat plane, thereby rendering it easier to vulcanize or otherwise secure the end member to the bent-over edge. This 60 will be apparent when it is observed that if the disks 17 were of substantially the same diameter as the tube the bent-over edge of the tube would be rounded in the region of the edge of the end member.

65 In Fig. 7 I have illustrated a modified

means for closing the outer casing, this means comprising two disks 23 and 24 clamping the pointed ends 25 of the outer casing therebetween. This construction differs from that shown in Fig. 1 in that bolts 70 26 are employed instead of the rivets 6, and in that the canvas disks 7 and 8 are omitted. With the construction shown in Fig. 7 the inner tube may be removed from the outer casing through the end of the outer casing by removing the bolts 26 and the disks 23 and 24, in which case the closing means 10-14 illustrated in Figs. 1 to 4 is unnecessary.

For the purpose of inflating the inner tube a valve 27 of the ordinary tire type is axially disposed at one end of the tube, the valve being secured to the tube by a nut 28 as usual and the valve extending outwardly through an axial opening in the outer casing 1. With the valve thus arranged the device may be inflated either before or after it is placed in a tire casing.

I claim:

1. In a device of the character described, 90 the combination of an air tube formed of flexible material and a flat member of flexible material closing one end of the tube.

2. In a device of the character described, 95 the combination of an air tube formed of flexible material and flat members formed of flexible material of substantially the same outline as the tube closing the opposite ends of the tube.

3. The method of closing the end of an 100 elastic tube which comprises inserting in the end of the tube a member of larger diameter than the tube, thereby expanding the tube, bending the edge of the tube over the member, and securing an end to the bent-over edge of the tube.

4. The method of closing the end of an 110 elastic tube which comprises inserting in the end of the tube a member having substantially the same contour as the tube but having a larger diameter than the tube, thereby expanding the tube, bending the edge of the tube over the member, and securing an end to the bent-over edge of the tube.

115 5. The method of closing the end of an elastic tube which comprises inserting in the end of the tube a member of larger diameter than the tube, thereby expanding the tube, bending the edge of the tube over the member, securing an end to the bent-over edge of the tube, and removing the disk.

6. The method of closing the ends of an 120 elastic tube which comprises inserting disks in the ends of the tube, bending the edges 125 of the tube over the disks, securing end members to the bent-over edges, and removing the disks through an opening in the side of the tube.

7. The method of closing a flexible tube 130

- which comprises inserting disks in the ends of the tube, bending the edges of the tube over the disks, securing end members to the bent-over edges, removing the disks through 5 an opening in the side of the tube, and sealing the opening in the side of the tube.
8. In a device of the character described, the combination of an inner tube adapted to be filled with air under pressure, an outer 10 casing arranged to confine the inner tube when inflated, the casing having an elongate opening in one side, and means comprising interfitting loops secured to the casing on opposite sides of the opening for 15 closing the opening.
9. In a device of the character described, the combination of an inner tube adapted to be filled with air under pressure, an outer casing arranged to confine the inner tube 20 when inflated, the casing having an elongate opening in one side, a plurality of loops secured to the casing on opposite sides of the opening so as to interfit with the loops in alinement, and a rod extending through 25 the loops.
10. A tube adapted to fit inside a tire having an elongate opening along one side, and means comprising interfitting loops secured to the tube on opposite sides of the opening 30 for closing the opening.
11. A tube adapted to fit inside a tire having an elongate opening along one side, a plurality of loops secured to the casing on opposite sides of the opening so as to inter- 35 fit with the loops in alinement, and a rod extending through the loops.
12. A casing of substantially cylindrical form, slit throughout its length, a plurality of loops secured to the casing on opposite edges of said slit so as to interfit with the loops in alinement, and a rod extending through the loops. 40
13. A casing of substantially cylindrical form, slit throughout its length, metallic members, each provided with a plurality of 45 loops, secured to the casing on opposite edges of the slit so as to interfit with the loops in alinement, and a rod extending through the loop.
14. In a device of the character described, the combination of a tubular casing having one of its end edges notched to provide a plurality of pointed sectors, said sectors being bent inwardly toward the axis of the casing and an end closure comprising two 55 disks clamping the sectors therebetween.
15. In a device of the character described, the combination of a tubular casing having one of its end edges notched to provide a plurality of pointed sectors, said sectors being bent inwardly toward the axis of the casing, flat disks embracing said sectors therebetween and rivets passing through 60 said disks and said sectors for clamping said sectors between said disks. 65
